CLAIM

I claim the ornamental design for a cushioned wrap for a strap of a knee pad, as shown and described.

DESCRIPTION

FIG. 1 is a perspective view of a cushioned wrap for a strap of a knee pad showing my new design;

FIG. 2 is a front view thereof;

FIG. 3 is a back view thereof;

FIG. 4 is a top view thereof;

FIG. 5 is a bottom view thereof;

FIG. 6 is a right side view thereof;

FIG. 7 is a left side view thereof; and,

FIG. 8 is a perspective view thereof, shown in a condition of use.

The broken lines depicting a fastening area are for the purpose of illustrating the unclaimed portions of the article and form no part of the claimed design.

The broken lines in FIG. 8 represent environmental structure and form no part of the claimed design.
